A. MIELE

PICK CONTAINER

Filed Aug. 15, 1925

UNITED STATES PATENT OFFICE.

ADOLPH MIELE, OF PITTSBURGH, PENNSYLVANIA.

PICK CONTAINER.

Application filed August 15, 1925. Serial No. 50,408.

This invention relates to holders or containers and more in particular to containers to be used in connection with string-instruments played by means of picks.

The primary object of this invention is to provide a container for picks which is readily adapted to be secured to the tail-pieces of banjos, mandolins, guitars, or other similar pick-operated instruments for the purpose of greatly reducing the loss or mislaying of picks. Another object of this invention is to provide a container for picks which is very compact in size, artistic and which can be manufactured at low cost. Additional features and advantages of this invention will appear from the following description considered in connection with the accompanying drawing forming a part of this application and in which:—

Fig. 1 is a cross-section through my pick-container as applied to a mandolin.

Fig. 2 is a front elevation of the container in its closed condition.

Fig. 3 is a longitudinal section through a container, mounted on a mandolin, for instance.

Fig. 4 is a perspective view of a tail-piece as commonly used on mandolins and banjos.

Fig. 5 is a perspective view of the base-portion of the container.

Fig. 6 shows in perspective the application of the pick-container to a banjo.

Fig. 7 is a similar view showing a modified construction adapted especially for guitars and similar musical instruments using curled picks, instead of flat ones.

Referring to the drawings, my pick-container is to be used in connection with string instruments having tail-pieces substantially similar in shape to the one shown in Fig. 4. When required, instruments provided with different kinds of tail-pieces may have the latter substituted by tail-pieces adapted to my container, as the cost of such parts is generally very slight and the transformation very easily made.

Each tail-piece comprises a vertical portion 1 having struck-up lugs 2 to which the lower ends of the strings S of the instrument are fastened and screw apertures 3 for securing the tail-piece to the body of the instrument. The horizontal portion 4 of the tail-piece is bent along its two long sides to provide the two parallel guide-ribs 5.

The pick-container proper consists of the

base B and the cover C, both made preferably of stamped metal. The base B comprises a bottom 6 the long sides of which are folded downwardly to form the grooves 7 adapted to slidably engage the guide-ribs 5 of the tail-piece. An extension 8 is provided at the lower end of the base to cover up the lower ends of the strings S, said extension being preferably given some artistic shape to improve the general appearance of the device.

The four sides of the container are produced by stamping out of the bottom 6 the rectangularly disposed lugs 9 and 10. The height of the latter is reduced to a minimum compatible with the thickness and the number of picks P which are to be stored in the container in order to not interfere with the proper playing of the instrument. If desired, raised strips 11 may be struck out of the bottom for inserting therebetween the picks P and prevent their rattling about in the container, while the instrument is being played.

The cover is hingedly mounted on the base by means of a pin 12 which is inserted in the buckles 13 and 14 provided respectively on the cover and the base. Opposite the buckles there is provided on the cover the downwardly directed resilient catch-tongue 15 which is adapted for snap-engagement with the corresponding side of the base. A spring 16 is also used to normally clamp the cover on the base and prevent the falling out of picks.

As shown especially in Figs. 2 and 6, the cover is preferably given a fanciful shape, such as that of a lyra, to improve the artistic appearance of my invention.

As stated before, the modification shown in Fig. 7 is intended to be used on string instruments using the more voluminous curled-picks, such as the guitar. Such picks require considerably higher containers than flat picks, and for that reason, said containers would interfere with the playing of the instrument if placed on top of the latter. Mechanically speaking, the construction of this modification is substantially identical to the one described above and it varies only in that the container is mounted on the vertical portion 1 of the tail-piece, thereby offering no handicap to the free movements of the player's arm. Also, for purely practical reasons, the hinge-connection 17 between the base and the cover is preferably placed at

the bottom and the catch-tongue 18 at the top of the container.

As will be understood, as suggested herein, there may be slight changes made in the construction and arrangement of the details of my invention without departing from the field and scope of the same, and I intend to include all such variations, as fall within the scope of the appended claims, in this application, in which the preferred forms only of my invention have been disclosed.

I claim:

1. A pick-container for a stringed musical instrument having a tail-piece, said container comprising a box-like base and a cover hingedly mounted thereon, and means for securing said base directly to the tail piece of said instrument.
2. A pick-container for a stringed musical instrument having a tail-piece, said container comprising a box-like base and a cover hingedly mounted thereon, and means provided on said base for slidably engaging the tail piece of said instrument.
3. A pick-container for a stringed musical instrument having a tail-piece, said container comprising a box-like base; a cover hingedly mounted thereon; means provided on said base for slidably engaging said tail piece, and resilient means for normally closing said cover upon said base.
4. A pick-container for a stringed musical instrument having a tail-piece, said container comprising a box-like base; a cover hingedly

mounted thereon; means provided on said base for slidably engaging said tail piece; resilient means for normally closing said cover upon said base, and means provided in said base for securing picks therein.

5. A pick-container for a stringed musical instrument having a tail-piece, said container comprising a box-like base; a cover hingedly mounted thereon; means provided on said base for slidably engaging said tail piece; resilient means for normally closing said cover upon said base, and means formed integrally with said base for securing picks therein.

6. A pick-container for a stringed musical instrument having a tail-piece, said container comprising a box-like base; a cover hingedly mounted thereon; means provided on said base for slidably engaging said tail piece, said base having strips struck-up from the bottom thereof and in spaced parallel relation thereto for the purpose of inserting picks.

7. A pick container for a stringed musical instrument having a tail-piece, said container comprising a base; a cover therefor; means provided on the base for slidably engaging said tail-piece; said base having struck up portions forming the vertical sides of said container and strips struck up from the bottom and in spaced parallel relation thereto for the purpose of inserting picks.

In testimony whereof I affix my signature.

ADOLPH MIELE.
